UNITED STATES PATENT OFFICE.

LEWIS W. CRAFT, OF CHICAGO, ILLINOIS, ASSIGNOR OF ONE-HALF TO JAMES GODFREY,
OF CHICAGO, ILLINOIS.

BOILER-FLUE JOINT.

1,164,577.

Specification of Letters Patent. Patented Dec. 14, 1915.

Application filed April 3, 1915. Serial No. 19,007.

To all whom it may concern:

Be it known that I, LEWIS W. CRAFT, a citizen of the United States, residing at Chicago, in the county of Cook and State 5 of Illinois, have invented new and useful Improvements in Boiler-Flue Joints, of which the following is a specification.

This invention relates to boiler flue joints, and it has for its object to effect improvements in the art of connecting a boiler flue 10 with the flue sheet.

Heretofore it has been found difficult to produce a thoroughly leak-proof flue joint owing to the expansion and contraction 15 caused by variations in temperature. The present invention has for its object to produce a construction whereby absolute contact between the flue sheet and the flue will be maintained at all times irrespective of 20 the degree of temperature.

A further object of the invention is to produce a leak-proof flue joint which will be simple in construction, which will not involve the use of auxiliary ferrules or 25 thimbles and which will be effective in operation.

With these and other ends in view which will readily appear as the nature of the invention is better understood, the same consists in the improved construction and novel 30 arrangement and combination of parts which will be hereinafter fully described and particularly pointed out in the claims.

In the accompanying drawing has been 35 illustrated a simple and preferred form of the invention, it being, however, understood that no limitation is necessarily made to the precise structural details therein exhibited, but that changes, alterations and 40 modifications within the scope of the claims may be resorted to when desired.

In the drawing, Figure 1 is a sectional view showing a portion of a flue sheet and a flue projected therethrough. Fig. 2 is a 45 similar view showing the flue forced to its seat. Fig. 3 is a similar view showing the appearance after the flue has been expanded. Fig. 4 is a similar view showing the appearance after the formation of the inner 50 bead.

Corresponding parts in the several figures are denoted by like characters of reference.

The flue sheet S having the opening 15 is provided with an annular groove or recess

16 surrounding and concentric with said 55 opening. The inner and outer side walls 17, 18 of the groove 16 are straight and parallel, as clearly seen in Fig. 1.

The flue 19 which is to be fitted in the opening 15 is provided at its outer end with 60 an annular lip or flange 20 which is turned back to a position parallel with the body of the flue or with the axis thereof. This lip, which may be conveniently formed by the use of proper tools, is spaced from the 65 body of the flue a distance equal to the distance between the groove 16 and the opening 15, so that said lip by forcing the outer end of the flue in the direction of the flue sheet will enter the groove 16 and completely fill the latter, suitable pressure being applied in any well known manner to properly assemble the parts. The assembled 70 position is shown in Fig. 2. After the flue has been assembled with the sheet, the outer 75 end thereof is expanded with the result that the material lying between the opening 15 and the groove 16 is forced or tilted outward, together with the portion of the lip 20 that lies within the groove, said portion 80 being tilted outward in the direction of the outer wall 18 of the groove. The portion 21 of the material of the flue sheet lying between the opening 15 and the groove 16 will thus coöperate with the lip 20 to form a 85 beveled joint whereby the parts will be very intimately assembled. This construction is particularly indicated in Fig. 3. The parts having been assembled in the manner described, I next form on the flue, adjacent 90 to the inner face of the flue sheet, an annular bead 22, indicated in Fig. 4 of the drawings, said bead being upset against the inner face of the flue sheet and forming a 95 tight joint therewith, as best seen in Fig. 4.

It will be seen that by the construction described, the flue is provided with a back-turned lip lying parallel to the axis of the flue, and, therefore, capable of being readily assembled with the flue sheet having the annular groove with parallel side walls surrounding the flue opening. By the subsequent expansion of the flue, the material of the flue as well as that of the flue sheet is tilted in the direction of the outer side walls 100 of the groove, thereby forming a lock joint that prevents the outward displacement of the flue, said lock joint being reinforced by 105

the formation of the bead 22 which also cooperates with the flue sheet to form a tight joint.

When expansion takes place due to increase in temperature, the diameter of the opening 15 is decreased, while the diameter of the flue is increased, and the parts are thus intimately wedged together. When contraction takes place due to reduction of temperature, the tendency will be for the diameter of the opening 15 to become enlarged, while the diameter of the flue becomes reduced. Under these circumstances it is obvious that with the construction customarily resorted to leakage is liable to take place. Under my improved construction as herein shown and described, when contraction takes place, due to reduction of temperature, that portion of the flue sheet indicated at 21 which lies between the opening 15 and the groove 16 will expand against the back-turned lip 20 of the flue, the diameter of which is lessened, thus preserving a perfectly tight joint, the loosening or disassembly of the parts being prevented, partly due to the fact that by expanding the outer end of the flue, the parts are tilted to form an inclined lock joint and partly owing to the presence of the internal bead 22.

Having thus described the invention, what is claimed as new, is:

1. A flue sheet having a flue opening and an annular groove surrounding the same, and a flue having a back-turned lip engaging said groove, said flue being expanded, the material lying between the inner wall of

the groove and the outer wall of the flue being tilted in an outward direction because of said expansion.

2. A flue sheet having a flue opening and an annular groove surrounding the same, and a flue having a back-turned lip engaging said groove, said flue being expanded, the material lying between the inner wall of the groove and the outer wall of the flue being tilted in an outward direction because of said expansion, and said flue being provided with an annular bead adjacent to the inner face of the flue sheet.

3. The improvement in the art of assembling a flue with a flue sheet which consists in providing the flue sheet with an annular groove surrounding the flue opening therein, said groove having parallel walls; forming on the outer end of the flue a back-turned lip lying parallel to the axis of the flue, forcing the outer end of the flue in the direction of the flue sheet to cause the lip to enter the annular groove, expanding the outer end of the flue to tilt in an outward direction the material lying between the inner wall of the groove and the outer wall of the flue, and forming on the flue an annular bead adjacent to the inner face of the flue sheet.

In testimony whereof I affix my signature in presence of two witnesses.

LEWIS W. CRAFT.
